DEVELOPING, FIXING, AND WASHING TANK

Filed Dec. 7, 1927

UNITED STATES PATENT OFFICE

CLAYTON L. DREW, OF SAN FRANCISCO, CALIFORNIA

DEVELOPING, FIXING, AND WASHING TANK

Application filed December 7, 1927. Serial No. 238,312.

This invention relates to improvements in combined developing, fixing and washing tanks for photographic purposes.

The principal object of this invention is to provide means whereby a strip of film may be effectively developed, fixed and washed without handling while wet, thereby eliminating any danger of scratching the surface of the film.

10 Another object is to provide means whereby a film may be wound upon a reel in such a manner as to maintain the various convolutions separated one from another.

15 A further object is to provide means whereby any fluid placed in the tank may be effectively circulated about all parts of the film.

20 Other objects and advantages will be apparent during the course of the following description.

In the accompanying drawings forming a part of this specification and in which like numerals are employed to designate like parts throughout the same,

25 Figure 1 is a side elevation of my complete tank,

Figure 2 is a vertical cross section of Figure 1,

Figure 3 is a bottom plan view of the developing reel,

Figure 4 is a horizontal cross section of the developing reel,

Figure 5 is a top plan view of the developing reel showing the manner of placing the film thereon,

Figure 6 is a top plan view in reduced size showing the position the reel takes within the tank, and

Figure 7 is a side elevation of my modified form of reel.

In the developing of photographic film particularly of motion picture type, it has been necessary for the amateur to have his film developed at a commercial place where large tanks are employed.

Applicant has therefore devised a tank whereby the amateur may develop his own film at home in as satisfactory a manner as is done in a commercial establishment.

50 In the accompanying drawings wherein

for the purpose of illustration is shown a preferred embodiment of my invention, the numeral 5 designates a cup-like tank having a cover 6, which cover has a downturned edge 7 and is further provided with an auxiliary 55 downturned flange 8 which is secured to the top 6. This arrangement provides for a rubber gasket 9 which is adapted to contact the top of tank 5 when the cover is placed upon the tank. Secured to one side of the tank is 60 an overflow tube 11 which has communication through an opening 12 with the interior of the tank. In order to prevent light passing through the tube 11, a light trap is provided at 13 which effectively traps any light 65 which may pass through the opening 12.

It is obvious that this overflow tube 11 might be equally well placed in the cover 6 if desired. A funnel is shown at 14, which funnel is provided with a downwardly extending tubular portion 16. This tubular portion is soldered or otherwise secured to the cover 6 and is provided with breather openings 17 therethrough, the purpose of which will be later seen. A concentric ring 18 surrounds the tubular extension 16 and is also secured to the cover 6. 70 75

Referring now to Figures 3, 4 and 5 it will be noted that I have provided a reel consisting of a top portion 19 and a bottom portion 80 21 which are held in spaced relation as by a hub portion 22. The hub portion carries a spring element 23, the purpose of which will be later seen.

The adjacent surfaces of the top and bottom of the reel are each provided with a spiral groove as shown at 24. By now referring to Figure 3, it will be noted that the bottom portion is provided with an annular rim 26 and with concentric rings 27 and 28. 85 These concentric rings are split as shown at 29 and 31 respectively. It will also be noted from this figure that the hub portion 22 is tubular in construction and that openings 32 permit the flow of liquid through the bottom member as will be hereinafter described.

In the modified form shown in Figure 7, the construction is identical with the exception that the tube 33 which forms the hub is secured to the bottom member 34 and is some- 90 95 100

what elongated, which bottom member is similar in construction to the bottom member 21 and that the top member 36 which is similar to the top member 19 is provided with a boss 37 having a set screw 38. This permits the top member to be spaced from the bottom member a predetermined distance and then secured in that adjusted position. I have provided slots 39 and 40, which slots serve to act as a gauge for adjusting the distance between the top member and the bottom member to accommodate films of this width.

At 41 I have shown the ordinary spool commonly employed for winding film therein and it will be noted that by placing the edge of the ends of the spool in the slots 39 and 40, the same act as a gauge for spacing the top and bottom members so that the reel will accommodate the width of film carried upon that particular spool.

The manner of employing my device is as follows:—

The film is first removed from its holder whether it be a spool as shown at 41 or a holder as shown at 42, which type of holder is employed in many camera using moving picture films. After the film has been removed from the holder, the end is passed between the thumb and first finger as shown in Figure 5 and by slightly compressing the film so that it is narrower than the distance between the adjacent surfaces of the top and bottom members, the end may be passed beneath the spring 23 after which the reel is rotated in a counter clockwise direction maintaining the film in the same condition, the result being that after the film is wound onto the reel it will flatten out and enter the grooves at the opposite sides of the reel, thus spacing each convolution as the reeling progresses. After the film has been wound upon the reel, the reel is placed upon the tank as shown in Figure 2 and the cover placed thereon. The remainder of the developing operation may be completed in the daylight, the loading of the reel having taken place in the customary dark room.

The developer is now poured into the funnel 14, the same flowing down through the tubular hub and out through the openings 31 thence around through the opening 29 and upwardly through the openings 32 (see the arrows at the bottom of Figure 2). Any air which is trapped in the tank will escape as shown by the arrows at the top of Figure 2. This will permit the tank to fill and thus cover the reel and film while thereon. When the developing operation has been completed, the tank is turned on edge so that the developer will run out of the overflow tube 11. The fixer is now poured into the funnel and allowed to stand the requisite time after which the film may be inspected if desired, to see if the fixing operation has been completed. As soon as the fixing has been com-

pleted the entire device is placed under a faucet and the water turned on. The water will thus flow through the funnel 14 thence as shown by the arrows at the bottom of this Figure 2 and will pass out of the overflow tube 11. The washing operation is continued as long as necessary with the result that an even flow of water will pass over all of the surface of the film thereby effectively washing the

By now removing the reel from the tank the end of the film may be grasped and pulled therefrom allowing the reel to rotate in a clockwise direction, after which the film is hung up to dry.

It will thus be seen that by employing my tank, the film may be developed, fixed and washed without any possibility of scratching the surface of the film which is of extreme importance when developing small negatives which are to be enlarged, as any scratch will be magnified.

It is to be understood that the form of my invention herewith shown and described is to be taken as a preferred example of the same and that various changes relative to the material, size, shape and arrangement of parts may be resorted to without departing from the spirit of the invention or the scope of the subjoined claims.

Having thus described my invention, I claim:—

1. In a device of the character described, a tank comprising a cup-shaped portion, a cover adapted to tightly engage the said tank, a tubular member extending through said cover and terminating closely adjacent the bottom of said tank, a reel adapted to be positioned within said tank, said reel comprising a tubular hub portion adapted to surround said tubular member and having a top portion and a bottom portion secured thereto, the adjacent faces of said top portion and said bottom portion each having a spiral groove formed therein, film holding means carried on said hub portion and means for circulating a liquid poured through said tubular member over the surface of the film carried by said grooves.

2. In a developing tank of the character described, a receptacle, a reel positioned within said receptacle, said reel having a hollow hub portion and adapted to have a film wound thereon with the convolutions of the film in spaced relation, said reel having its ends provided with perforations, and an annular peripheral flange on the end of said reel and contacting with the bottom of said receptacle whereby liquid entering the hub of said reel will be directed upwardly through said perforations.

3. In a device of the character described, a developing reel comprising a tubular hub portion, a top portion and a bottom portion secured to said hub, a spiral groove formed in each of the adjacent faces of said top and bot-

tom members the distance between the adjacent faces of said top and bottom members being less than the width of the film to be developed therebetween, a receptacle adapted to hold said reel, said receptacle comprising a cup-like tank having a cover position thereon, filling and overflow means whereby said tank may be filled and emptied, light excluding means for preventing the admission of light to said receptacle through said filling and overflow means, said light excluding means comprising circuitous passages through the filling and overflow means respectively.

In testimony whereof I affix my signature.
CLAYTON L. DREW.
